DESIGN FOR A COMBINED GLOBE AND PANEL FOR A LIGHTING FIXTURE

Edward C. Zimmerman and Robert G. Nordquist,
Chicago, Ill., assignors to Patent License Cor-
poration, Chicago, Ill., a corporation of Illinois

Application December 11, 1940, Serial No. 97,256

Term of patent 14 years

To all whom it may concern:

Be it known that we, Edward C. Zimmerman and Robert G. Nordquist, citizens of the United States, residing at Chicago, in the county of Cook and State of Illinois, have invented a new, original, and ornamental Design for a Combined Globe and Panel for a Lighting Fixture, of which the following is a specification; reference being had to the accompanying drawing, forming a part thereof.

In the drawing:

Fig. 1 is a front face view of a combined globe and panel for a lighting fixture, showing our new design;

Fig. 2 is a side view of the same; and
Fig. 3 is an end view of the same.

We claim:

The ornamental design for a combined globe and panel for a lighting fixture, substantially shown.

EDWARD C. ZIMMERMAN
ROBERT G. NORDQUIST.
